UNITED STATES PATENT OFFICE.

JOHN P. LITSEY, OF CHICAGO, ILLINOIS.

GLOBE-SUPPORTING DEVICE.

No. 818,103.

Specification of Letters Patent.

Patented April 17, 1906.

Application filed September 21, 1905. Serial No. 279,561.

To all whom it may concern:

Be it known that I, JOHN P. LITSEY, a citizen of the United States, residing at Chicago, in the county of Cook and State of Illinois, have invented certain new and useful Improvements in Globe-Supporting Devices; and I hereby declare the following to be a full, clear, and exact description of the invention, such as will enable others skilled in the art to which it appertains to make and use the same.

My invention relates to an improvement in educational appliances, and more particularly to means for supporting geographical globes in a desired position with their axes at a desired inclination and the globe itself at a convenient height for examination and study; and it consists in the features of construction and combination of parts hereinafter fully described and claimed.

In the accompanying drawings, illustrating my invention, Figure 1 is a perspective view of a globe, showing it suspended from a ceiling, the suspension devices being constructed in accordance with my invention. Fig. 2 is an enlarged side elevation of a portion of the meridian-ring and the supporting-clamp. Fig. 3 is an enlarged vertical section on the line 3 3 of Fig. 2. Fig. 4 is a fragmentary central section of the globe and meridian-ring, the ring being shown partly in elevation.

In studying globes, especially those of twelve inches in diameter or larger, it has been found convenient to be able to support them at different heights and to incline their axes at different angles in relation to the position of the student and also to have them supported in such a manner that the globe may be swung in a horizontal circle about the observer as a center, the plane of the meridian being always maintained in the north and south plane. It is also convenient to so mount the globes that they may be quickly and easily raised entirely out of the way when not in use. To accomplish the above, I have provided the means which I will now describe.

In said drawings, 1 illustrates a globe which is revolvably mounted on the axis 2, which is removably mounted in the meridian-ring 3. The meridian-ring 3 is provided with oppositely-disposed annular flanges 4 at its outer edge, and the U-shaped clamp 5 is provided, which is adapted to receive the flanges 4 between its jaws 6, the free ends of said jaws being bent inwardly to engage the

inner faces of said flanges, so that when said clamp is suspended the meridian-ring will be held dependent therefrom, the weight of the globe and meridian-ring holding said ring suspended in a vertical plane. Said clamp 5 is provided with a clamping-bolt 7, which passes through holes in said jaws 6, and said jaws are adapted to be drawn tightly against said flanges by same. The hole in one of said jaws is square, and the shank 7 of said bolt immediately beneath its head is square and adapted to fit in said square hole to prevent said bolt from turning, and the opposite end of said bolt is threaded and provided with the thumb-nut 8, whose operation is obvious. Said clamp 5 is provided on its base with two oppositely-disposed laterally-extending arms 9, which incline upward at a slight angle, the free ends of said arms being provided with perforations 10, adapted to receive hooks or other devices to connect said clamp to suspending cords or wires 11. Said suspending-cords pass upward, preferably divergent, over pulleys 12, suspended from the ceiling or other convenient support. They are then brought together and secured to the single cord 13, which is trained over a pulley 14, preferably located adjacent a convenient wall, and a balance-weight 15 is secured to its free end. The globe 1 is thus suspended in a manner which makes it convenient to raise and lower it very easily. By loosening the clamping-bolt 7 the meridian-ring may be easily moved through said clamp and the axis of the globe 1 adjusted to any desired inclination, and by again tightening said clamp it will remain securely in that position.

In hanging globes for study it is preferable to hang them so that their meridian-ring lies in a north and south plane and to maintain the meridian in that plane regardless of the various positions of the globe itself. The clamp which I have devised and which is provided with the supporting-arms rigidly attached thereto effectually prevents the rotation of the meridian into any other plane than the one intended unless the supporting-cords are forcibly revolved around each other. This action is entirely different from what it would be if there were a swivel connection between the supporting-arms and the clamp. The axis 2 of said globe is mounted in radial holes in the said ring, the center line of said radial holes passing through the ninety-degree point, and consequently it does not alter

the latitude-reading of any point on the surface of the globe when the inclination of the axis or pole is changed, as occurs when the axis is mounted in a separate movable ring 5 mounted within the meridian - ring. Said axis comprises a rod 16, which is turned down at its ends to form the bearings or pivots 17 and 18, the pivot 17 being much shorter than the pivot 18. Radial holes 19 and 20 are 10 drilled in the inner edge of said meridian-ring for the reception of said pivots 17 and 18, respectively, said hole 20 for said pivot 18 being quite deep and adapted to receive the small coiled compression-spring 21 between 15 the end of said pivot and the bottom of said hole. Said spring 21 is adapted to hold said axis endwise, with the shoulder 22 at its opposite end pressed firmly against the inner edge of said meridian-ring, and as said axis is 20 longer between said shoulder and the free end of said pivot 18 than the inner diameter of said meridian-ring said axis is thus held securely in its proper position. Thimbles 23 and 24 are provided, mounted upon said rod 25 16 and adapted to enter the central opening 25 of the bar 26 within said globe 1, whereby said globe is revolvably mounted upon said axis. To remove said globe from said meridian-ring, said rod 16 is forced endwise against 30 the action of said spring 21 until the free end of said pivot 17 is free from said meridian-ring, when the ring may be passed to one side and the opposite end of said rod withdrawn from same. The solid axis, as illustrated, 35 has been found to be much stronger and permanent than the divided axis in common use. Suitable stops 27 may be arranged on said supporting-cords to engage said pulleys or their frames, thereby preventing said globe 40 from being raised or lowered too far.

My device is very simple, strong, and durable and easily manipulated.

I claim as my invention—

1. The combination with a geographical 45 globe provided with a meridian-ring, of means for revolvably mounting said globe in said ring, means for adjustably mounting said ring as to height and the inclination of said globe, comprising an axis adapted to be 50 mounted in the ring and receive said globe, and said ring being provided at its outer edge

with an annular flange on each face, a clamp comprising two jaws, adapted to bear upon the edges of said flanges, projections-on the free ends of said jaws adapted to extend 55 within said annular flanges and engage the inner faces of same, means for forcing said jaws toward each other; oppositely-disposed laterally-extending rigid supporting-arms on said clamp, cords attached to the free ends of 60 said arms, supporting-pulleys, said cords being drawn over said pulleys and a balance-weight attached to the free ends of said cords, substantially as described.

2. The combination with a geographical 65 globe provided with an axial opening and a meridian-ring, of means for revolvably mounting said globe in said ring and means for adjustably mounting said ring as to height and inclination of the axis of said globe, comprising 70 an axis adapted to be mounted in said ring and receive said globe, said axis being reduced at its ends to form pivots and shoulders and said ring being provided with radially-disposed openings adapted to receive 75 said reduced ends a compression-spring in one of said openings adapted to hold said axis endwise so that the shoulder at its opposite end engages the inner face of said ring, said ring being provided at its outer edge 80 with an annular flange on each face, a clamp comprising two jaws adapted to bear upon the edges of said flanges, projections on the free ends of said jaws adapted to extend 85 within said annular flanges and engage the inner faces of same, means for forcing said jaws toward each other; oppositely-disposed laterally-extending rigid supporting-arms on said clamp, cords attached to the free ends of 90 said arms, suitable supporting-pulleys, said cords being trained over said supporting-pulleys and a balance-weight attached to the free end of said cords substantially as and for the purpose described.

In testimony whereof I have signed my 95 name in presence of two subscribing witnesses.

JOHN P. LITSEY.
